RIVET BUCKER

Robert J. Townsend, Donelson, Tenn.

Application November 27, 1943, Serial No. 511,975

2 Claims. (Cl. 78—53.5)

This invention relates to new and useful improvements in rivet buckers and more particularly to a bucker for flattening the ends of aluminum rivets in a one man operation.

The principal object of the present invention is to provide a rivet bucker which can be used inside of wings, ailerons and various other structures for bucking rivets, especially aluminum rivets, to the end that riveting of this category can be done single handedly whereas at present at least two men are necessary.

Various other important objects and advantages of the invention will become apparent to the reader of the following description.

In the drawings:

Figure 1 is a fragmentary vertical sectional view showing the bucker inserted into work.

Figure 2 is a top plan view of the bucker.

Figure 3 is a fragmentary detailed sectional view taken on the line 3—3 of Figure 2.

Figure 4 is a fragmentary longitudinal sectional view taken on the line 4—4 of Figure 2, after the bars of the bucker have been released to expanded position.

Figure 5 is a fragmentary detailed sectional view similar to that of Figure 4, but showing the bar and one of the rivets after the rivet has been flattened.

Figure 6 is a fragmentary sectional view showing a modified form of bucker used in conjunction with parallel sides of work.

Referring to Figure 1, wherein like numerals designate like parts, it can be seen that numeral 5 denotes a piece of work which may be a portion of an aileron. Numerals 6 denote rivets disposed through overlapping portions of the sheet material of which the aileron is constructed, while numeral 7 generally refers to the present invention which is inserted into the aileron and released to engage the rivets as shown in Figure 4.

The device 7 consists of a pair of bars 8, 9, each of which at its outer side has a strip 10 of some protective material so as to not scratch the surface of the aileron. Each part at its outer side and extending through the covering 10 has recesses 11 for receiving the inner ends of aluminum rivets 12 which project inwardly through openings in the work 5.

Projecting inwardly from the bars 8, 9 are small studs 13 which project into the end convolutions of compression springs 14.

A pair of link bars 15, 16 each has one end pivotally secured as at 17 to the corresponding bars 8, 9, while the remaining ends are pivotally

secured together as at 18. The bar 16 has a pivotal detent hook 19 which is engageable with an eye 20 on the pivotal bar 15 as is clearly shown in Figure 1. Thus the bars 8, 9 can be held in contracted relation to permit insertion of the device 7 into the work, after which upon release-
ment of the detent hook 19, the springs 14 will force the bars 8, 9 apart to engage the rivets as shown in Figure 4.

10 Slotted members 21 project from the bar 8 and receive the laterally disposed end portions 22 of arms 23 which project inwardly from the bar 9, thus defining guide means for the bars 8, 9.

Suitable handles 24 are provided for the bars 15 8, 9 so that they may be manually actuated.

Obviously, when the detent hook 19 has released the bars 8, 9 they will assume the position shown in Figure 4. The riveting tool in acting on the rivet will vibrate the device 7 and this will 20 function as a bucker for the rivet, to the end that the rivet is flattened as shown in Figure 5.

Figure 6 is a modification of the invention, reference character 5a denoting work into which the modified device generally referred to by reference character 7a is inserted. This form of the invention is used for work having parallel sides and consists of straight bars 8a, 9a having handles 24a and springs 14a interposed between the same as in the manner of the device shown in 25 Figure 1. The bars 8a, 9a have pivotal connecting bars 15a, 16a and latch means 19a. The outer sides of the bars 8a, 9a have protecting strips 10a and are formed with rivet receiving recesses 11a.

30 35 While the foregoing specification sets forth the invention in specific terms, it is to be understood that numerous changes in the shape, size and materials may be resorted to without departing from the spirit and scope of the invention as 40 claimed hereinafter.

Having described the invention, what is claimed as new is:

1. An insertable rivet bucker comprising a pair of opposed bucking bars and spring cushioning 45 means interposed between the bars, said bars having recesses for receiving rivets projecting through the enveloping work.

2. An insertable rivet bucker comprising a pair of opposed bucking bars and spring cushioning 50 means interposed between the bars, and holding means for holding the bars in contracted position against the force and effect of the spring means.

ROBERT J. TOWNSEND.
